US00D816693S

(12) **United States Design Patent** (10) Patent No.: **US D816,693 S**
Dong et al. (45) Date of Patent: ** May 1, 2018

(54) **DISPLAY SCREEN OR PORTION THEREOF WITH GRAPHICAL USER INTERFACE**

(71) Applicant: **Samsung Electronics Co., Ltd.**, Suwon-si (KR)
(72) Inventors: **Jongsung Dong**, Suwon-si (KR); **Seong-Ji Kang**, Seoul (KR); **Hye Kang Roh**, Seoul (KR); **Gunguk Park**, Suwon-si (KR); **Young Jun Seo**, Yongin-si (KR); **Hoyong Jung**, Busan (KR)

(73) Assignee: **SAMSUNG ELECTRONICS CO., LTD.**, Suwon-si (KR)

(**) Term: **15 Years**

(21) Appl. No.: **29/567,951**

(22) Filed: **Jun. 14, 2016**

(30) **Foreign Application Priority Data**

Dec. 21, 2015 (KR) 30-2015-0065321

(51) LOC (11) Cl. **14-04**

(57)

CLAIM

The ornamental design for a display screen or portion thereof with graphical user interface, as shown and described.

DESCRIPTION

The FIGURE is a front view of a display screen or portion thereof with graphical user interface showing our new design.

The broken lines in the drawings show portions of the display screen or portion thereof with graphical user interface that form no part of the claimed design.

1 Claim, 1 Drawing Sheet
